(57) **CLAIM**

The ornamental design for a modular utility rack, as shown and described.

DESCRIPTION

FIG. 1 is a perspective view of a modular utility rack showing our new design;

FIG. 2 is a front plan view thereof;

FIG. 3 is a right plan view thereof;

FIG. 4 is a left plan view thereof;

FIG. 5 is a top plan view thereof;

FIG. 6 is a bottom plan view thereof; and,

FIG. 7 is a rear plan view.

The break lines on the edges of the shelves, and the four legs in FIGS. 1 through 7 are not part of the claimed design and represent that no particular length is claimed.

The broken lines showing is included for the purpose of illustrating environment and forms no part of the claimed design.
